(No Model.)

M. S. WRIGHT.

STOP ACTION FOR ORGANS.

No. 310,239.

Patented Jan. 6, 1885.

UNITED STATES PATENT OFFICE.

MORRIS S. WRIGHT, OF WORCESTER, MASSACHUSETTS, ASSIGNOR OF ONE-HALF TO ALICE P. CARPENTER, OF SAME PLACE.

STOP-ACTION FOR ORGANS.

SPECIFICATION forming part of Letters Patent No. 310,239, dated January 6, 1885.

Application filed September 19, 1883. (No model.)

To all whom it may concern:

Be it known that I, MORRIS S. WRIGHT, a citizen of the United States, residing at Worcester, in the county of Worcester and State 5 of Massachusetts, have invented certain new and useful Improvements in Stop-Actions for Organs; and I declare the following to be a description of my said invention sufficiently full, clear, and exact to enable others skilled 10 in the art to which it appertains to make and use the same, reference being had to the accompanying drawings, which form a part of this specification.

In the drawings, Figure 1 is an end view 15 of such parts of an organ-action as will illustrate the nature of my invention. Fig. 2 is a plan view of the same. Fig. 3 is a sectional view of a stop-pull with dotted lines to illustrate the positions of action. Fig. 4 is a diagram illustrating the action of the mute-connections. Fig. 5 is a view of one of the mute-connecting wires, and Fig. 6 shows the form 20 and arrangement of the ends of the rocker-rods in connection with the pulls.

In a complete organ-action there are a greater 25 number of stops than here shown, and it will be understood that a greater or less number of such stops can be arranged in the series for operating in substantially the same manner as herein described, some being connected for 30 single action and others for combined action, according to the requirements of the instruments; but as the arrangement of the individual devices are substantially similar for each 35 of the mutes, it will not be necessary to herein show and describe the entire organ-action.

The features of my invention consist in the 40 construction and manner of arranging pull and rocker connections and the adaptation of the devices for operating one or more rocker-rods by independent or combined action, as hereinafter explained.

In the reference to parts, A denotes the reed-board; B, the brace, and C the mutes, which 45 parts may be respectively constructed and located in relation to the manual and sounding devices in any suitable or ordinary manner.

D, D', and D² indicate stop-pulls, two of 50 which are shown as adapted for operating separate mutes independently, while the other,

D', shows the construction as adapted for operating two or more mutes simultaneously, or for combining the effect of the two stops D and D² by operation of a single pull. The pulls are arranged through guiding-openings in the 55 name-board B' and back strip, b, and are provided with suitable knobs or heads, whereby they can be drawn out in the usual manner for changing the stops.

E designates the rocker-rods, formed of heavy 60 wire, and arranged through suitable bearings, f, f', upon the top of the brace-board B, as illustrated. The inner ends of the rocker-rods are turned upward, as at e, and respectively pass through slots d in the pull-bars D and D'. They 65 are then extended laterally, as at e', to the central pull, D', and are then turned downward to give engagement with offsets or lugs on the sides of said central pull. The sides of the pull-rod D' are slabbed off, as indicated 70 at d', and lug-pieces l are attached at the rear end of the slabbed-off portion, to facilitate engagement of the pull with the ends of the rocker-rod wires at both right and left. The outer ends of the rods E are bent at right 75 angles or offset, as at E', to give the requisite swing or crank action for moving the mutes C, which latter are connected thereto by means of wires F, the ends of which are respectively hooked into slotted blocks g, fixed on the end 80 of the rocker-arm E', and to suitable arms or projections on the mutes C, as illustrated. Each rocker-rod arm E' and its connecting-wire F are so arranged that the force exerted 85 by the springs employed for closing the mutes, 85 acting through the wire F, serves for retaining the parts when the stops are drawn out and the mutes are open, as well as for retaining them in place when the stops are not drawn. This action is illustrated in Fig. 4, the full lines 90 showing the position when the stop is drawn or open, and the dotted line when the stop is closed. When the connection is swung back as far as the dotted line w, the stop will move the remainder of the distance to close by the 95 recoil of the springs on the mutes. Upon the top of the pulls are arranged spring-wires I, carrying at their forward ends latch dogs or blocks i, which fall in front of the rocker-arms e' when the pull is drawn forward, (see full 100

line, Fig. 3,) and serve for engaging with and swinging said arms backward with the backward movement of the drawn pull. The spring I is made with an incline or bend at I', which 5 rides up on the top edge of the back piece, b, with the extreme backward movement of the pull, thereby raising the dog i clear from the arm e' of the rocker-rod, as shown by dotted lines, Fig. 3, leaving said arm free to be moved 10 forward independent of the pull on which the respective spring and dog is located. The slabbed portion of the pull D' and the slots d of the pulls D and D² are of sufficient length to permit the arms e to swing forward independent of the movement of the pull. By this 15 arrangement of parts the particular pulls D and D² act on the rocker-rods when drawn each independently, while the pull D', when drawn, operates both of the rocker-rods simultaneously and without moving the pulls D and D², since the latch-dogs on said pulls being raised 20 permits the arms e to swing forward and back in the slots d with the action of the pull D'.

In any stop where it is not desired to combine the action the part of the wire rod e' can 25 be omitted, the arm e simply terminating at the top of the pull D.

What I claim as my invention, and desire to secure by Letters Patent, is—

1. The combination, with the rocker-rod 30 having an arm, e, of the pull-bar provided with the spring I, having the bend I' and latch-dog i, and the support-piece b, as and for the purpose set forth.

2. The combination of the rocking rods E E, 35 provided with arms e and laterally-extended top portions e', the pulls D D², and the pull D', severally provided with springs I and dogs i, all adapted for operation substantially as and for the purpose set forth. 40

Witness my hand this 27th day of August, A. D. 1883.

MORRIS S. WRIGHT.
